[57] CLAIM

The ornamental design for a mobile handset telephone and stand therefor with integral speakerphone and magnetic card reader, as shown and described.

DESCRIPTION

FIGS. 1 and 2 are respectively front and rear elevational view of a mobile handset telephone and stand therefor with integral speakerphone and magnetic card reader showing my new design in cradled relationship; FIGS. 3 and 4 are respectively right and left side elevational views thereof;

FIGS. 5 and 6 are respectively top and bottom plan views thereof;

FIGS. 7, 8 and 9 are respectively sectional views taken on the lines (1) VII—VII in FIG. 1, (2) VIII—VIII in FIG. 1, and VIII—VIII in FIG. 1, and IX and IX in FIG. 3, with interior construction omitted in all three figures;

FIG. 10 is a left side, bottom front side perspective view of the handset and stand in cradled relationship; and FIG. 11 is a bracketed right side, underside, and front perspective view of the handset and a left side, top and front of the perspective view of the stand alone.

The showing of cord in fragmentary form in sundry figures is for convenience and clarity of illustration.
